(No. Model.)

C. W. KING & A. CLIFF.
GAS ENGINE.

No. 293,179.

Patented Feb. 5, 1884.

UNITED STATES PATENT OFFICE.

CHARLES WILDEN KING, OF MANCHESTER, AND ALFRED CLIFF, OF LONDON,
ASSIGNORS TO PHILIP MIDDLETON JUSTICE, OF CHANCERY LANE,
LONDON, ENGLAND.

GAS-ENGINE.

SPECIFICATION forming part of Letters Patent No. 293,179, dated February 5, 1884.

Application filed April 9, 1883. (No model.) Patented in England October 24, 1879, No. 4,337; in France April 24, 1880, No. 136,313; in Belgium April 27, 1880, No. 54,303; in Germany May 8, 1880, No. 12,188; in Canada October 13, 1880, No. 11,849; in Italy October 16, 1880, No. 40; in Austria December 21, 1880, No. 5,321, and in Spain April 26, 1881, No. 1,366.

To all whom it may concern:

Be it known that we, CHARLES WILDEN KING and ALFRED CLIFF, residents, respectively, of Broughton Bridge Iron Works, Manchester, England, and Southampton Buildings, London, England, have jointly invented certain Improvements in Gas-Engines, of which the following is a specification.

Our invention relates to that class of gas engines in which a charge or mixture of gas and air exploded within a cylinder is the means of forcing out the piston, the spent gases being then expelled to a greater or less extent prior to another explosion; and our invention consists, chiefly, in the means hereinafter fully described, whereby the excess of spent gases is removed from the cylinder, the main object being to secure such expulsion prior to the return of the piston, so that it can condense and compress the fresh charge on its backward movement.

In carrying out our invention we may employ the engines illustrated in the accompanying drawings. We, moreover, do not limit ourselves to such constructions, as the improvement may be employed in many engines otherwise made.

In the drawings, Figure 1 is a transverse vertical section of an engine illustrating our invention. Fig. 2 is a sectional view illustrating another form of engine.

The power-cylinder E receives the reciprocating piston F, which is connected by its rod to the crank of the driving-shaft N, which carries the usual fly-wheel. The cylinder is secured to a base, W, of any proper construction, and is provided with a port, x, for the admission of the charge of gases. This charge may be pumped into the cylinder and exploded, as is common; or it may be exploded in a chamber embracing or communicating with both the cylinder and a separate chamber, A, contained within a casing, A', as will be more fully described hereinafter. Whatever may be the manner in which the gases are conducted to the cylinder and exploded, the explosion will force forward the piston and fill the cylinder with non-explosive or waste gases. Commonly, in gas-engines, the gases are expelled in whole or in part by the backward move-

ment of the piston, an exhaust-port being opened at the rear during such movement. This is attended with many disadvantages. For instance, when the back movement is required to expel the spent gases the next charge cannot be admitted until the piston again moves forward, so that the charge must be exploded without compression; or it must be compressed in a separate cylinder, and even in such case there is apt to be a loss from expansion prior to explosion. This can be avoided by exploding only once in every four strokes; but there is a loss of power and an uneven action. We overcome these difficulties by placing the exhaust-port g' near the forward end of the cylinder, so that after the explosion and after the piston has traveled the greater portion of its stroke the exhaust is opened and the spent gases escape. If the new charge is pumped into the rear of the cylinder, or enters the same under pressure, or is otherwise induced to enter the cylinder, it forces forward a greater or less portion of the spent gases, which pass through the exhaust after the piston uncovers the same; or, if the fresh charge is not forced in at such time, the opening of the exhaust permits the gases to escape under their own pressure until there is no longer any pressure in the cylinder in excess of the atmosphere.

In the apparatus shown in the drawings the chamber A is surrounded at the upper end by a chamber or coil, through which cold water is circulated, so as to maintain this end cool, while the opposite end, which becomes heated by the explosion of the gases, remains in that condition, a non-conducting packing, w, separating the two portions. Within the chamber A reciprocates a plunger, B, which is hollow and contains wire-gauze, which, becoming heated, heats the air or gas which passes through the same. The air enters the end of the chamber A through a port, e, closed by a valve, h, and the gas through a port, s, also closed by said valve, and an electrical igniter, V, serves to explode the gases.

In Fig. 1 the piston has a flanged or hollow projection, t, which has circumferential recesses f, that coincide for a time with the exhaust-port until there is an equilibrium of pressure within and without the cylinder,

when the further outgo of the piston will close the exhaust, and the air and gas will be drawn through the end port into the lower end of the chamber A as the piston completes its outward movement. The piston, returning, covers the exhaust-port and compresses the charge, when the plunger B rises and the gas is carried to the hot end of the chamber, where it is heated and expanded, producing a great increase of pressure just as the piston begins its outward stroke, immediately after which a current is passed to the igniter and the charge exploded. As the piston moves outward, the plunger descends, so that the gases will be transferred from the bottom to the top of the chamber A, and those in the cylinder will pass out of the discharge-port when the latter is opened, while the fresh-heated gases pass to the rear of the cylinder.

20 In Fig. 2 is shown a pump, C, which forces a new charge of gas and air into the cylinder E as the exhaust-port is uncovered by the forward motion of the piston, so that before the latter returns and covers said port the entering charge will to a greater or less degree have forcibly expelled a portion of the spent gases. As the inlet and outlet ports are at separate points, the waste gases flowing out through the discharge will not carry with them any material portion of the fresh charge. The fresh charge is compressed by the backward motion of the piston, and as it is exploded while compressed and heated the full force of the combustion is secured.

35 While differently-constructed electrical or other igniters may be employed, that illustrated will be found effective. It consists of a detachable metal plug, D, fitting an opening in the cylinder, and carrying two insulated platinum wires, z z; slightly separated at their inner ends, and connected to wires leading to the battery X, or other source of electricity. The circuit is made and broken at any time to secure a spark between the wire-45 terminals at the moment an explosion is required. This construction permits the plug to be removed readily as often as necessary to examine the device.

Another form of igniter is shown in Fig. 2, 50 which may be used when it is desired to maintain a constant flame within the receiver. h' h' are a number of wire-gauze disks fitted in the passage and maintained rigid by a plate, k' k', of copper or iron pierced full of small 55 holes. The pump delivers the mixture under these disks, and the flame, not being able to strike back through them, keeps alight by the residual gas contained in the space o' o' in the intervals between the strokes of the 60 pump.

In order to start the engine, the electrical igniter D is used.

The displacing-plunger B is worked by a cam or other device so constructed that it will 65 move quickly in either direction, and then come to a rest.

We do not here claim the means described for heating the gases prior to introducing them into the cylinder, and we reserve for subsequent applications for Letters Patent 7c such novel features as are not herein specifically claimed.

We claim--

1. The combination, in a gas-engine, of a cylinder having an exhaust-port communicating freely with the external atmosphere, 75 as described, near its forward end; inlet-port near the rear end, and appliances constructed to open said exhaust for the discharge of spent gases, while the working-piston is at or near the forward position to which it is moved by the explosion of the gases, substantially as set forth.

2. The combination, in a gas-engine, of a cylinder provided with ports near its opposite ends, and means, substantially as described, for supplying an explosive charge at the inner end of the cylinder, and for opening the exhaust as the piston nears its forward position, whereby the incoming fresh charge 90 is made the means of expelling spent gases through the exhaust, substantially as set forth.

3. The combination of the cylinder having its exhaust and inlet ports at separate points 95 in the cylinder, and a pump and connections whereby the fresh charge is forced in when the exhaust is open, substantially as set forth.

4. The combination of a cylinder having an inlet-port near the rear end, and means for 100 introducing the charge under pressure, and an exhaust-port near the forward end, arranged to be uncovered by the piston as the latter approaches its forward position, and means for then closing the exhaust, so that the further 105 forward movement aids to draw in the new charge, as set forth.

5. The combination of a cylinder having an inlet-port at the rear end, an exhaust which is closed by the piston except when the latter 110 is in a forward position, and means for controlling the ports, substantially as described, whereby each fresh charge is admitted to expel spent gases, is compressed on the inward stroke, and is exploded to impart the outward motion to the piston, substantially as 115 set forth.
